James J. Conroy

UNITED STATES PATENT OFFICE.

JAMES J. CONROY, OF ST. PAUL, MINNESOTA.

RADIATOR HANGER.

Application filed May 29, 1924. Serial No. 716,673.

This invention relates to a supporting device, and particularly to such a device adapted to support a radiator such as the heat radiators now commonly employed in buildings.

- 5 It is becoming a very general practice to support radiators in buildings from the wall rather than to have supporting legs on the radiators. When the radiators are supported from the wall there is a clear, free floor 10 space beneath the same which can be kept much cleaner and in a more sanitary condition than if there are supporting legs contacting the floor. Radiators are made in different heights to suit different buildings and 15 are also made in different widths, as two columns, three columns, four columns, etc. Such radiators commonly comprise sections connected by a pipe or conduit adjacent the bottom of the sections. While other radiator 20 supporting brackets have been proposed, they have generally been such that different styles and parts are required for different sized radiators and for radiators of different heights. A supply house for these brackets now has to 25 carry a very large number of different sizes and styles so that it is a very frequent occurrence that when the brackets are sent for the radiators of a large building that there are too many of one type and not enough of 30 another. This causes delay and great trouble to the contractors installing the radiators. The radiator brackets commonly in use also comprise lengths of pipe or rods which have to be cut and threaded on the job so that a 35 great deal of work is necessitated on the contractor's part after he has purchased the regular radiator supporting brackets.

It is an object of this invention, therefore, to provide a simple and efficient radiator support which can be used with all different types 40 and different heights of radiators.

It is a further object of this invention to provide such a universal radiator support including a flexible member engaging the radiator and secured to supporting means attached to the wall.

It is still another object of the invention to provide a radiator support comprising a bracket adapted to be secured to the wall and 45 having means engaging the radiator, which bracket supports a member beneath the same which, preferably, is vertically adjustable or extends around a portion of the radiator for supporting the same.

50 It is still another object of the invention to

provide such a radiator support, as above set forth, carrying adjacent its bottom a block adapted to abut the wall and the radiator for holding the radiator in vertical position.

It is also an object of the invention to provide a radiator support comprising a bracket adapted to be secured to a wall having a forwardly extending means adapted to be secured to the radiator and also carrying a depending means including a flexible member for supporting the radiator, said depending means and said forwardly extending means being constructed and arranged for relative lateral adjustment on said bracket.

It is more specifically an object of this invention to provide a radiator support comprising a bracket adapted to be secured to a wall, a rod or bolt depending therefrom, a member having spaced portions adjustably supported by said rod, one of said portions carrying a flexible member engaging and supporting the radiator and the other of said portions carrying a block adapted to abut the wall and said radiator.

These and other objects and advantages of the invention will be fully set forth in the following description made in connection with the accompanying drawings in which like reference characters refer to the same parts throughout the different views, and in which

Fig. 1 is a view in front elevation of a radiator of the common type with the support thereon;

Fig. 2 is a view in side elevation, as seen from the right of Fig. 1;

Fig. 3 is a horizontal section taken on the line 3—3 of Fig. 2;

Fig. 4 is a horizontal section taken on the line 4—4 of Fig. 2;

Fig. 5 is a vertical section taken on the line 5—5 of Fig. 3, Figs. 3, 4 and 5 being shown on an enlarged scale;

Fig. 6 is a view similar to Fig. 3 showing a modification; and

Fig. 7 is a view in front elevation of the structure shown in Fig. 6.

Referring to the drawings, a wall against which a radiator is to be secured is indicated as 1 and the floor extending therefrom as 2. A base board 3 is shown positioned against the wall adjacent the floor and a strip of molding 4 is shown at the foot of the base board. A radiator of the common type now used for heating purposes is illustrated com-

prising the sections 5 spaced longitudinally of the radiator and being connected by a pipe or conduit 6 adjacent the bottom thereof. The sections 5 are shown as having contacting lugs 5^a adjacent their tops and the sections may also be connected by rods 7 extending longitudinally of the radiator.

The supporting device for the radiator includes a bracket 8 adapted to be secured to the wall by one or more bolts or other convenient fastening means 9 anchored in the wall. It is a common practice in modern building construction to place the attaching bolts or similar members in wall when the same is built, the radiator being afterwards attached thereto. While the bracket 8 may be of various forms, in the embodiment of the invention illustrated, the same is shown as in the form of a substantially U-shaped plate having front and rear vertical portions connected by the bottom portion 8^a. In the form shown in Figs. 1 to 4, a bolt or threaded rod 10 extends forwardly from the front vertical portion of bracket 8 between the radiator sections 5 and engages a plate 11 extending transversely of and in contact with the inner columns of the sections 5, said rod 10 being threaded into the plate 11. The plate 11 can thus be drawn tightly against the radiator so that the same is held in engagement with the bracket 8. The bottom portion 8^a of the bracket has an opening 8^b extending therethrough and a shouldered recess 8^c is formed in said bottom above the opening 8^b. Said recess is adapted to receive a washer or circular plate 12 having circumferentially spaced projecting short teeth 12^b at its periphery adapted to seat in similar notches formed about the edge of recess 8^c. The plate 12 has an opening therethrough eccentrically thereof and a headed bolt or rod 13 depends through said opening. The washer 12 is readily removable so that the same can be rotated and held in various rotated positions in the bracket 8. The lower end of bolt 13 is threaded and extends through an opening in the top of a yoke member 14. While the yoke member 14 may be variously made, in the embodiment of the invention illustrated, the same is shown as made from a flat bar bent substantially into rectangular shape, the vertical parallel sides of the yoke preferably approaching each other at the top and being connected by the horizontal flat top portion 14^a. Said top portion is centrally apertured to receive the lower end of the bolt 13 and a nut 13^a is threaded on the bolt beneath the top portion 14^a so that the yoke is vertically adjustable on the bolt 13. The inner vertical side of the yoke is bent outwardly adjacent its end to form a lug 14^b. The outer vertical side of the yoke has its lower end bent inwardly and upwardly to form a lug 14^c and provided with a central slot 14^d for a purpose to be

later described. A bar 15 is secured to the outer side of the front vertical portion of the yoke 14 and adapted to abut or engage the inner sides of the radiator sections 5. It may be here noted that radiators, as now generally made, are of standard size of sections and the sections are arranged with their center lines 2½ inches apart. It is desirable, therefore, to have the front portion of brackets, as well as the plate 15, at least three 75 inches in length so that they will extend across two of the radiator sections. A flexible member 16 extends about the conduit 6 and has members 17 secured thereto at its ends, which members are considerably larger 80 in one dimension than the width of the slot 14^d. These members are disposed above the lug 14^c with the upper portions of the flexible member 16 disposed in the slot 14^d so that said flexible member and the pipe 6 are supported by said lug 14^c and yoke 14. The pipe 6 supports the radiator and the radiator is thus supported from the brackets 8 by the flexible member 16. The flexible member may take either the form of a metal cable or 85 a chain. The members 17 are preferably used with a metal cable and can be attached thereto by soldering, spot welding or by a suitable screw threaded into the members to engage said cable. If a chain is used the members 17 which will engage the lug 14^c may be secured to the chain in any suitable manner. A headed bolt or rod 18 extends through an opening in the lug 14^b and has its head resting on said lug and its lower end threaded. 90 A block 19 is apertured to receive the lower end of bolt 18 and supported thereby by a suitable nut 20 threaded onto said bolt. The block 19, preferably, is of greater thickness or height at its rear end than at its front end. The block 19 abuts the wall 1 at its inner side and abuts the radiator sections 5 at its outer side. Said block 19 will be made substantially the same width as the brackets 8 and will also preferably be at least three 95 inches long.

In the modification shown in Figs. 6 and 7, a bracket 21 similar to the bracket 8 is used but the same has merely a central hole in its bottom portion 21^a through which the bolt 13 extends. The front vertical side of the bracket, however, is provided with a transverse slot 21^b through which the bolt 10 passes. The rear side of the bracket is similar to that of bracket 8 and is attached to the 100 wall in the same manner.

In operation, in the form shown in Figs. 1 and 5, the bracket 8 will be secured to the wall by the bolts 9. The radiator will then be placed with the bolt 10 extending centrally 105 between the sections. The flexible member 16 will now be engaged with the pipe 6; the member 17 secured thereto and engaged with the lug 14^c on the yoke 14. The yoke will now be adjusted by means of a nut 13^a, until the 110

flexible member 16 is taut and the radiator is hung thereby. The block 19 will now be positioned to hold the radiator in vertical position and spaced from the wall. There will be a slight tendency in the radiator to swing in, and for the yoke 14 to swing out, but the parts are held in the desired position by a block 19 and by the plate 15 on the yoke coming against the radiator sections. It is sometimes necessary to have a lateral adjustment either of the bolts 10 or the bolts 13 in order that the same may be brought into position between the radiator sections. If this is necessary, the washer 12 can be raised and rotated and again seated in position. Owing to the eccentric disposition of the bolt 13 on the washer 12, said bolt can be placed in various lateral positions relative to the bracket 8 and the flexible member 16 thus brought into central position between the sections of the radiator.

In the modification shown in Figs. 6 and 7, the washer 12 is dispensed with and a slot is placed in the bracket 8 to permit of a lateral movement of the bolt 10 so that the same can be positioned centrally of the radiator sections.

From the above description it is seen that applicant has provided a simple and efficient support for a radiator. The support can be used with a two column, three column or other type of radiator and no change will be necessary except, perhaps a slightly different length of flexible member 16. The other parts will remain just the same for all types of radiators. It will also be seen that the support can be used with a radiator of any height, the only difference being in the length of the flexible member 16. The block 19 will be adjusted to suit the height of the radiator. The flexible member 16 will have one of the members 17 secured thereto before being taken to the place of installation and the other member can be secured in position to suit the type and height of the radiator on which it is used. The plate 15 is prevented from turning by the sides of the yoke 14 and the nut 20 is prevented from turning by being seated in the bottom of block 19. The radiator support is easily and inexpensively made from simple material which is easily secured and bent into the desired shape. The device has been amply demonstrated in actual practice and found to be successful and efficient.

While the brackets 8 and 21 have been described as being adapted to be attached to a wall, it will be understood that the term "wall" is used in a broad enough sense to include a ceiling to which said brackets might in some cases be secured.

It will, of course, be understood that various changes may be made in the form, details, arrangement and proportions of the parts without departing from the scope of ap-

plicant's invention, which, generally stated, consists in a device capable of carrying out the objects above set forth, such as shown and described and defined in the appended claims.

70

What is claimed is:

1. A device adapted to support a radiator having in combination, a bracket adapted to be secured to a wall, means adapted to secure said bracket to the upper portion of the radiator, a member carried by said bracket, means for positioning and holding said member in different vertical and lateral positions, and a flexible means carried by said member adapted to extend outwardly and downwardly from said member and about the lower portion of the radiator for supporting the same.

2. A device adapted to support a radiator having in combination, a bracket adapted to be secured to a wall, a member carried below said bracket, means for supporting said member from said bracket for positioning said member in different vertical and lateral positions and at different distances from said wall, a flexible means carried by said member and extending downwardly and outwardly therefrom, adapted to pass around a portion of the radiator and support said radiator, a rod depending from said member and a block adjustably carried by said rod adapted to engage said radiator and be disposed between the same and said wall and between the bottom of the radiator and the top of said flexible means.

3. A support for a radiator having in combination a bracket adapted to be secured to a wall and having a portion adapted to engage a radiator, means adapted to connect said bracket and radiator, a member depending from said bracket and laterally adjustable therein, a member comprising spaced portions supported by said last mentioned member, flexible means connected to one of said portions and adapted to engage the radiator, and a block carried by the other of said spaced portions and adapted to abut the wall and the radiator.

4. A hanger for a radiator having in combination a bracket adapted to be secured to a wall, a rod depending from said bracket, means on said bracket supporting said rod, a yoke carried by said rod and vertically adjustable thereon, a flexible member carried by said yoke and adapted to engage and support the radiator, a rod depending from said yoke, and a block carried by said last mentioned rod adapted to engage the wall and the radiator.

5. The structure set forth in claim 4, said yoke having a plate secured to its front side adapted to engage the radiator.

In testimony whereof I affix my signature.

JAMES J. CONROY.
